US00D867383S

(12) **United States Design Patent** (10) Patent No.: **US D867,383 S**
Wang et al. (45) Date of Patent: **** Nov. 19, 2019**

(54) **DISPLAY SCREEN OR PORTION THEREOF WITH A GRAPHICAL USER INTERFACE**

(71) Applicant: **BEIJING BYTEDANCE NETWORK TECHNOLOGY CO., LTD.**, Beijing (CN)

(72) Inventors: **Dapeng Wang**, Beijing (CN); **Zi Xiong**, Beijing (CN); **Kunyu Shi**, Beijing (CN)

(73) Assignee: **BEIJING BYTEDANCE NETWORK TECHNOLOGY CO., LTD.**, Beijing (CN)

(**) Term: **15 Years**

(21) Appl. No.: **29/653,587**

(22) Filed: **Jun. 15, 2018**

(30) **Foreign Application Priority Data**

Dec. 15, 2017 (CN) 2017 3 0642977

(51) **LOC (12) Cl.** **14-04**

(52) **U.S. Cl.**

USPC **D14/486**

(57) **CLAIM**

We claim the ornamental design for a display screen or portion thereof with a graphical user interface, as shown and described.

DESCRIPTION

The FIGURE is a front view of a display screen or portion thereof with a graphical user interface showing our new design.

The broken lines shown in the FIGURE represent portions of the display screen or portion thereof with a graphical user interface that form no part of the claimed design.

1 Claim, 1 Drawing Sheet
